ANODE STRUCTURE FOR ELECTRON
DISCHARGE DEVICESPercy L. Spencer, West Newton, Mass., assignor to
Raytheon Manufacturing Company, Newton,
Mass., a corporation of Delaware

Application October 26, 1949, Serial No. 123,647

1 Claim. (Cl. 315—40)

1

This invention relates to electron discharge devices, especially, but not necessarily, of the magnetron type, and more particularly to the anodes of such devices.

In high power devices of the general character indicated, especially those designed for the generation of microwave energy, it is usually necessary, in the interest of heat dissipation, either to build the anode of excessively large size, or provide the same with complicated cooling arrangements. It is to the elimination of these disadvantages that the present invention is primarily addressed.

It is among the objects of the present invention to provide an anode for an electron discharge device which is simple in construction, yet capable of high heat dissipation.

It is a further object of the present invention to provide an anode, having the foregoing desirable characteristics, which is inexpensive to fabricate and assemble and which is of reasonable size.

These and other objects of the present invention, which will become more apparent as the detailed description thereof progresses, are attained, broadly, in the following manner.

The invention contemplates the provision of a hollow tubular member which is alternately bent in opposite directions to provide anode arms separated by cavity resonators. Preferably, after so bending the hollow member, it is formed into a circle and mounted in a cylindrical body which may then be hermetically sealed. The resulting radially disposed anode arms define a central space in which a cathode may be mounted, and, when such a structure is provided with a suitable potential difference between the cathode and the anode, and an appropriate axial magnetic field is applied parallel to the cathode, microwave energy may be generated of a frequency primarily depending, in a manner well known to those skilled in the art, on the geometry of the cavity resonators intermediate the anode arms. The ends of the tubular member, between which there is a continuous passage, are brought out of the envelope, one end functioning as an inlet for a coolant, such as water, and the other end functioning as an outlet for such coolant. By maintaining a constant coolant flow, the anode is maintained at a suitably low temperature and an efficient high power microwave generator of reasonable size results.

In the accompanying specification there shall be described, and in the annexed drawing shown,

an illustrative embodiment of the anode structure of the present invention. It is, however, to be clearly understood that the present invention is not to be limited to the exact details herein shown and described for purposes of illustration only, inasmuch as changes therein may be made without the exercise of invention and within the true spirit and scope of the claim hereto appended.

10 In said drawing:

Fig. 1 is a longitudinal sectional view of an electron discharge device including an anode made in accordance with the present invention; and

15 Fig. 2 is a transverse sectional view taken along line 2—2 of Fig. 1.

Referring now more in detail to the aforesaid illustrative embodiment of the present invention, with particular reference to the drawing illustrating the same, the numeral 10 generally designates an electron discharge device of the magnetron type. Such a tube comprises, broadly, a cathode structure 11, an anode structure 12 spaced from and surrounding said cathode structure, and means 13 for establishing a magnetic field in the interelectrode space, in a direction transverse to the electron path between the cathode and the anode structures.

While not limited thereto, the cathode structure 11 may comprise a cathode sleeve 14 provided with any preferred electron-emissive coating 15, said sleeve being carried by a tubular member 16, the outer end of which carries another tubular member 17. Mounted within the sleeve 14 is a cathode heater 18, one end of said heater being electrically connected, as at 19, to said sleeve, and the other end being connected to a lead-in conductor 20 which passes downwardly through the tubular members 16 and 17, insulated therefrom by beads 21 and 22. The tubular member 16 carries, adjacent the outer end thereof, a heat-radiating structure 23.

The entire cathode structure 11 is supported from the anode structure 12 by securing the tubular member 16 to a ferrule 24 which depends from an insulating sleeve 25, in turn, depending from a tubular member 26. The latter is carried in a recess formed in a pole piece 27 secured to the anode structure 12, said pole piece being provided with a central bore through which the cathode structure enters the anode structure. The pole piece 27, together with another pole piece 28, and an external magnet not shown, constitute the means 13 for establish-

ing the previously referred to magnetic field in the space between the cathode and anode structures.

The anode structure comprises a cylindrical body 29 closed at its ends by end caps 30 and 31, said end caps carrying the pole pieces 27 and 28, and the entire anode structure being evacuated and hermetically sealed.

Mounted in the cylindrical body 29 is a hollow tubular member 32, said member, as best seen in Fig. 2, being alternately bent in opposite directions to provide electron receiving anode arms 33 separated by cavity resonators 34. The member 32 is, after formation of the anode arms and intervening cavity resonators, formed into a circle whereby the anode arms become radially disposed, with the inner ends thereof defining a cathode space 35. The cavity resonators open at one end into the space 35, and the member 32 may be fixed into the cylindrical body by brazing at points opposite the closed ends of said cavity resonators.

The outer ends of the hollow member 32 communicate with the exterior of the anode structure 12 and may be connected to provide, respectively, an inlet and outlet for a coolant, such as water, which, in circulating through the continuous passage between the inlet and outlet ends of the member 32, maintain the anode structure at a reasonably low temperature.

The device is completed by a conventional output loop 36 extending into the anode structure 12 and disposed adjacent the upper or lower edge of one of the anode arms 33.

When the cathode sleeve 14 is heated to thermionic emission, as by a source of voltage 37, and the anode structure is maintained at a suitable positive potential with respect to the cathode, as by a source of voltage 38, the device described oscillates to generate microwave energy of a frequency depending, primarily, on the physical structure of the cavity resonators incorporated in the anode structure.

This completes the description of the aforesaid illustrative embodiment of the present invention. It will be noted from all of the fore-

going that the present invention provides an anode for an electron discharge device which is simple in construction, easy and economical to fabricate and assemble, may be made of a reasonable size, and is highly efficient in dissipating the large quantities of heat generated in a microwave generator designed for delivering energy at high power levels.

Other objects and advantages of the device of the present invention will readily occur to those skilled in the art to which the same relates.

What is claimed is:

A magnetron comprising: a hermetically sealed cylindrical envelope; a cathode centrally disposed in said envelope; and an anode spaced from and surrounding said cathode; said anode including a hollow flattened tubular member successively bent in opposite directions to provide alternate arms facing said cathode and intervening arms secured to said envelope; each adjacent pair of the arms facing said cathode, together with the arm therebetween secured to said envelope, defining a cavity resonator of appreciable dimension in the direction of said cathode; said hollow tubular member providing a continuous passage between the ends thereof, and said ends communicating with the exterior of said envelope and constituting, respectively, fluid inlet and outlet ports.
